DESIGN FOR AN AX OR SIMILAR HAND TOOL

Walter W. Rector, Cleveland, Ohio, assignor to
The American Fork & Hoe Company, Cleveland,
Ohio, a corporation of Ohio

Application August 15, 1939, Serial No. 86,695

Term of patent 14 years

To all whom it may concern:

Be it known that I, Walter W. Rector, a citizen of the United States, residing at Cleveland, in the county of Cuyahoga and State of Ohio, having invented a new, original, and ornamental Design for Axes or Similar Hand Tools, of which the following is a specification, reference being had to the accompanying drawing, forming a part hereof, in which:

Fig. 1 is a side plan view of an ax showing my design;

Fig. 2 is a top plan view of the design in Fig. 1;
Fig. 3 is a rear plan view of the design in Fig. 1.

I claim:

The ornamental design for an ax or similar hand tools, substantially as shown.

WALTER W. RECTOR.
